UNITED STATES PATENT OFFICE.

LEO FRANKENFELD, OF HOBOKEN, NEW JERSEY.

EXERCISING APPARATUS.

Application filed May 14, 1925. Serial No. 30,159.

This invention relates to an improved exercising apparatus.

The main object of the invention is to provide an improved form of exercising apparatus which is complete in itself, and is at all times available for use at any place or position at which it is desired to use the same, without necessitating the use of hooks or other fixtures which have to be attached to a floor, wall or other such means of support, the apparatus being designed to permit easy and ready connection or disconnection or adjustment of the effective length of exercising devices or elements, and also to prevent or reduce to a minimum the possibility of accident or mishap due to breakage of connections.

Another object of the invention is to provide an extremely simple but strong and efficient construction of exercising apparatus adapted to occupy a minimum of space when not in use and adapted to be very easily and quickly set up for use to enable various exercises to be performed by the use thereof.

25 The invention is illustrated in the accompanying drawings in which:

Figure 1 is a view in perspective of an exercising device in accordance with the present invention.

30 Fig. 2 is an enlarged view showing the means employed for connecting the individual exercising devices or elements to the base of the apparatus.

Fig. 3 is a view similar to Fig. 2 but showing a slightly modified form of connecting means between the exercising devices and the base or platform, and

40 Fig. 4 is an enlarged view of one of the exercising devices or elements forming part of the improved apparatus.

Similar numerals refer to similar parts throughout the several views.

The exercising apparatus according to this invention, as shown in Fig. 1 of the accompanying drawings, consists of a base or platform 1, which may be made of any suitable material, such as wood, or may be a stamping of metal, such as aluminum. The base or platform is made of sufficient size to enable a person to stand comfortably thereon, or to sit or lie thereon according to the nature of the exercises which are to be performed, the weight of the person in any place holding the base or platform firmly upon the floor or ground. The base or platform may be made in one piece as shown, or

it may be made in two sections of equal size hinged together by means of hinges so as to enable one section to be folded over upon the other for purposes of storage or transport. 60

Attached by suitable means, such as screws, to the under side of the base 1, is a metal strip or plate 3, extending across the width of the base, and bent up at its outer ends to provide at each end an upwardly extending lug or bracket 4 extending above the upper surface of the base, each lug or bracket being provided with an aperture or apertures 5 therein.

The individual exercising devices or elements of which there are a plurality marked 6 and 7 are attached to the base through the medium of a connecting element extending between the apertured lugs or brackets 4 of the base, which connecting element is of a flexible nature and permits of ready adjustment of the points of connection of the ends of the exercising elements, and at the same time serves to limit the upward movement of the end or eye of the exercising element in the case of breakage so as to prevent accident or mishap. 70

This connecting element in the particular form of exerciser as illustrated in Figs. 1 and 2 of the drawings, comprises a length of 85 chain 8 which is connected at its ends to the apertured lugs or brackets 4 of the base or platform 1. The end links of the chain may be connected directly to the lugs 4 or they may be connected to somewhat larger links 90 9 which are connected to said lugs. The links of the chain are preferably welded links so as to provide a chain or connecting element of great strength. The length of the chain 8 is much greater than the width of 95 the base or platform 1 so that in use the portion of the chain between the two side exercising elements 6 is positioned a suitable distance above the base so as to permit the person exercising to stand or sit comfortably 100 upon said base and to perform the desired exercises without interference.

The exercising devices 6 at opposite sides of the base or platform may be similar in construction, and each may comprise a handle or hand grip 10 having at least one eye 11 to which is attached by any usual or suitable form of connecting device 12 an elastic element 13. This elastic element may be a spring, or an elastic cord, as usual in exercising apparatus and it is attached by means of any suitable or usual connecting device 14 110

to one of the links of the chain 8. Preferably the handle 10 is provided with a plurality of eyes 11 so that a plurality of elastic cords or elements may be attached thereto and these elements or cords may be attached at their other ends to the same or different links of the chain 8.

It will be seen from Fig. 1 that the exercising elements or devices are securely connected by means of the chain 8 with the base or platform upon which the person stands so that the exercising elements may be expanded and retracted at will in different directions during the performance of different exercises the base or platform being securely held against the pull of the elastic elements during expansion thereof by the person standing or sitting upon the platform. The chain forms a very strong connection between the exercising devices and the base or platform, and the effective length of the exercising devices with respect to the base or platform may be readily changed or adjusted by connecting the connecting device 13 in different links of the chain as will be readily understood. It will also be seen that the chain forms a means for limiting the extent to which the end of an exercising device, or the connecting device at the end thereof, can fly upwardly in case of breakage of the connection between the exercising device and the base. Thus assuming that the connecting element or chain should break between the connecting device 13 and the lug 4, or in the case of breakage of said lug, the end of the exercising device can only fly upwardly to the extent permitted by the swing of the chain about the other lug 4 or about the point of connection of the lower end of the other exerciser 6. The extent to which the end of the exerciser can fly upwardly is thus limited to a relatively short distance so that the connecting device 13 cannot strike a vital part or organ of the body so that serious injury to the person exercising due to an accident of this nature is entirely prevented.

It will be understood particularly by reference to Fig. 3 that the connecting devices 13 of the exercising elements might be connected to one or other of additional links 14 connected to the length of chain, the connecting devices being connected in one or other of these additional links or being connected in the lower links of the chain as desired to permit the necessary adjustment of the effective length of the exerciser element. In this form of the connecting element or chain it may be considered to comprise a length of chain with additional links attached thereto intermediate the ends thereof, or it may be considered to comprise two lengths of chain extending upwardly from the apertured lugs 4 with a third length of chain connecting the two lengths of chain

first mentioned. The purpose and function of the chain or chains is exactly the same as that mentioned in connection with Figs. 1 and 2.

It is preferred to provide a third exercising device 7 attached to the base or platform 1 through the medium of the connecting element or chain 8 in order to permit a greater variety or scope in the number and nature of the exercises to be performed by the use of the apparatus. As shown in Figs. 1 and 4 this third exercising device or element comprises a loop member or belt 15 adapted to be placed around the waist or other part of the body of the person exercising, for example about the neck of the person so as to rest upon the shoulders. This loop or belt may be suitably formed of webbing or other material and may be adjustable as to its size by means of a buckle 16 or other fastening device of any usual or suitable form. This loop or belt is adapted to be connected at opposite sides thereof with the base or platform 1 by means of elastic elements or cords 17, one or more of which may be provided at each side of the loop or belt. These elastic elements or cords are preferably attached to the loop or belt 15 by bands or loops 18 of webbing or the like passing around the belt 15 and carrying rings 19 in which suitable or usual connecting devices 20 at the ends of the elastic members 17 are engaged. Preferably the belt 15 or the loops 18 are provided with flaps 21 to prevent the connecting devices 20 or the rings 19 from rubbing or chafing the person to whom the belt is applied. The other ends of the elastic members or cords 17 are provided with suitable or usual connecting devices 22 adapted to be connected into one or other of the links of the chain 8. The loops 18 may be arranged to be movable along the belt to adjust the relative position of the upper ends of the elastic elements 17 according to the nature of the exercise to be performed. This belt or loop exerciser is intended to be used by bending the body in different directions against the pull of the elastic members or cords, that is, assuming the person to be standing upon the base 1 with the belt 15 around the waist and with the elastic members 17 at his sides the exercise may be performed by bending the body sideways in opposite directions so as to alternately extend the elastic members. If the person stands on the base 1 with the body in a position at right angles to the position above referred to with the elastic members 17 at the front and rear the exercises may be performed by bending the body backwardly and forwardly to alternately extend the elastic members. In these uses of the belt exerciser it also serves as a reducing device for the removal or reduction of fatty tissue from the body. When applied about an upper part of the

person's body, for example, about the neck and resting upon the shoulders, the belt exerciser may be used to exercise various muscles of the neck and back by raising the upper

5 part of the body from a forwardly or rearwardly bent position against the pull of the elastic members, and during such exercise the loops 18 may be moved to a position closely adjacent each other either at the

10 front or at the rear of the belt.

The adjustment in height of the belt or loop 15 may be effected within certain limits by means of the adjustable connecting means formed by the chain 8, and where a greater 15 adjustment is desired elastic members or cords 17 of different lengths may be used or elastic members or cords, the effective length of which may be adjusted or varied, may be used.

20 It will be readily understood that the exercising apparatus of the present invention may be used in a large variety of ways, such as to exercise or develop practically all of the muscles of the body and at the same time 25 the structure of the apparatus is such that it may be easily and cheaply manufactured but yet will be strong and effective, and it may be used in any place, outdoors or indoors, and it may be readily carried about 30 or transported.

The invention is not limited to the precise details hereinbefore described as the various features of construction may be variously modified within the scope of the claims appended hereto. For example, the elastic members or cords of the exercising devices may be provided with devices for permitting adjustment of the length thereof either at the point of connection with the chain 8 or at 35 the point of connection with the handle 10, or in the case of the exerciser 7 at the point of connection with the chain 8 or at the point of connection with the belt 15, such for example as are described in my copending 40 application No. 641,301 filed May 25, 1923. Also instead of providing the bar or strip 3 in conjunction with the base or platform 1 a bar or strip might be employed provided with attaching lugs or brackets, 45 such as 4, and provided with transverse extensions or plates upon which the person exercising could stand so that the bar or strip would constitute a base or support having the same function as that of the base 50 or platform 1.

55 What I claim is:

1. Exercising apparatus, comprising in combination, a base member adapted to rest upon the floor, flexible connecting means 60 connected to opposite sides of said base member, and a plurality of independent exercising devices connected to said flexible connecting means, said means being such as to provide a plurality of connecting points for 65 said devices.

2. Exercising apparatus, comprising in combination, a base member adapted to rest upon the floor, a flexible non-extensible connecting element connected at opposite ends thereof to opposite sides of said base member, and a plurality of independent exercising devices connected to said flexible connecting element. 70

3. Exercising apparatus, comprising in combination, a base member adapted to rest upon the floor, a flexible connecting element connected at opposite ends thereof to opposite sides of said base member, and of greater length than the width of said member, and a plurality of independent exercising devices 80 connected to said flexible connecting element. 75

4. Exercising apparatus, comprising in combination, a base member adapted to rest upon the floor, a chain connected at opposite ends thereof to opposite sides of said base member, and a plurality of independent exercising devices connected to said chain. 85

5. Exercising apparatus, comprising in combination, a base member adapted to rest upon the floor, apertured lugs provided at opposite sides of said base member each bent up from a strip secured beneath said member, a flexible connecting element connected at opposite ends thereof to said lugs, and a plurality of independent exercising devices connected to said flexible connecting element. 90

6. Exercising apparatus, comprising in combination, a base member adapted to rest upon the floor, a flexible element connected at opposite ends thereof to opposite sides of said base member, and a plurality of independent exercising devices connected to said element, said element having a plurality of connecting points along the length thereof to 100 permit adjustable connection of the exercising devices therewith. 105

7. Exercising apparatus, comprising in combination, a bar to receive the feet of the person exercising, a flexible element connected at opposite ends thereof to opposite ends of said bar, and a plurality of independent exercising devices connected to said element. 110

8. Exercising apparatus, comprising in combination, a support adapted to rest upon the floor, a flexible non-extensible connecting element attached at opposite ends thereof to opposite sides of said support, elastic members attached at one end of each thereof to 115 said element, and a flexible loop member or belt to which the other ends of said elastic members are connected. 120

9. Exercising apparatus, comprising in combination, a support adapted to rest upon the floor, a flexible connecting element attached at opposite ends thereof to opposite sides of said support, elastic members attached at one end of each thereof to said element, a flexible loop member or belt, and 130

means adjustable along the length of said loop member or belt and to which the other ends of said elastic members are connected.

10. Exercising apparatus, comprising in combination, a support adapted to rest upon the floor, a chain attached at opposite ends thereof to opposite sides of said support, elastic members attached at one end of each thereof to said chain intermediate the ends thereof, and a flexible loop member or belt to which the other ends of said elastic members are connected.

11. Exercising apparatus, comprising in combination, a support adapted to rest upon the floor, flexible connecting means connected to opposite sides of said base member and providing a plurality of connecting points in the length thereof, elastic members attached at one end of each thereof to said connecting

means, and a flexible loop member or belt to 20 which the other ends of said elastic members are connected.

12. Exercising apparatus, comprising in combination, a support adapted to rest upon the floor, a flexible connecting element attached at opposite ends thereof to opposite sides of said support and providing a plurality of connecting points in the length thereof, a plurality of elastic members attached at one end of each thereof to said element, and a flexible loop member or belt to which the other ends of certain of said elastic members are connected, the remaining elastic members being provided with manipulating handles at the other ends thereof. 30 35

In testimony whereof I affix my signature.

LEO FRANKENFELD.
